SERVICE CONNECTER

George J. Meuer and Ralph A. Millermaster, Milwaukee, Wis., assignors, by direct and mesne assignments, of one-half to Cutler-Hammer, Inc., Milwaukee, Wis., a corporation of Delaware, and one-half to Borg-Warner Corporation, a corporation of Illinois

Original application July 16, 1934, Serial No. 735,443. Divided and this application May 1, 1935, Serial No. 19,132

8 Claims. (Cl. 173—324)

This invention relates to improvements in service connectors for electrical devices and more particularly to improvements in service connectors for electric refrigerators.

5 This application is a division of our application, Serial No. 735,443, filed July 16, 1934, for improvements in Service connectors.

The various electrical devices employed in an electric refrigerator, including the compressor 10 motor and its temperature responsive automatic control and a lamp for illuminating the interior of the refrigerator upon opening the refrigerator door, present a problem in providing a simple and convenient arrangement for connecting the same 15 to a source of current supply. Connector devices have been proposed having terminal elements to provide for connection of a pair of wires to the positive and negative lines, respectively, of a current supply source. In order to connect the electrical devices to the current supply it is necessary 20 to splice the separate wires from each of the devices to the two wires of the connector, necessitating the inconvenience and inefficiency of splicing, soldering and taping these connections. 25 These spliced connections may be more or less widely separated, or if, as has been proposed, a recess is provided in the cord receiving end of the connector to accommodate the taped connections, the splicing, soldering and taping is required to be accomplished in a limited space, 30 making these operations and the insertion of the knot of tapered wires into the connector very awkward and inefficient. In either case, the connections are potential sources of trouble, due to 35 faulty splicing or other causes, which are difficult to trace.

An object of the present invention is to provide a connector device which will overcome the aforementioned disadvantages and difficulties.

40 Another object is to provide a device of the aforementioned character in which terminal elements are provided, such terminal elements being so combined and related as to provide for convenient connection of all of the electrical devices of a refrigerator to a current supply source 45 and/or to each other without the necessity for spliced connections.

Another object is to provide a connector device which is simple and inexpensive in construction.

50 Another object is to provide a connector device having parts constructed and arranged to facilitate assembly thereof.

Another object is to provide a connector device 55 having terminal and contact elements of improved and simplified construction.

Various other objects and advantages of the invention will hereinafter appear.

The accompanying drawing illustrates an embodiment of the invention which will now be described, it being understood that the embodiment 5 illustrated is susceptible of modification without departing from the scope of the appended claims.

In the drawing, Figure 1 is a plan view of the contact blade and cord receiving end of a connector embodying our invention.

10 Fig. 2 is a plan view of the inner end of the base portion of the connector shown in Fig. 1, showing the arrangement of the terminal elements thereon.

Fig. 3 is a plan view of the lamp receiving end 15 of the connector.

Fig. 4 is a perspective view of the connector with parts thereof broken away for purposes of illustration; a typical refrigerator electrical system being shown diagrammatically in connection 20 therewith to illustrate the manner in which the same is employed.

Fig. 5 is a section on line 5—5 of Fig. 1.

Fig. 6 illustrates the manner of attachment 25 of the connector shown in Figs. 1 to 5 to a refrigerator motor control casing.

Fig. 7 is a flat development of a lamp screw shell and of the ring type lamp contact used in the connector shown in Figs. 1 to 6, inclusive, and

30 Figs. 8, 9 and 10 are views partly in elevation and partly in section, showing the manner of cooperation between the ring contact and the threads of the lamp screw shell; the sections of the ring being taken on lines 8—8, 9—9 and 10—10, respectively, of Fig. 7.

35 Referring to Figs. 1 to 6 of the drawing, the numeral 1 designates a connector, the parts of which include a molded insulating base 2 of cylindrical form. Said base is provided in its outer face with a circular recess 3 which is of reduced 40 diameter at its inner end, forming an annular shoulder 4 substantially midway between the outer end and the bottom wall of said recess. Adapted to seat within the recess 3 upon the diametrically opposed outwardly projecting bosses 45 5 and 6 on the annular shoulder 4 is a punched sheet metal, ring-shaped contact member 7. The inner edge of the ring 7 is provided with a substantially rectangular notch 8 to provide for the reception of the thread of a lamp screw shell, 50 and the area 9 radial to said notch is bent as shown in Figs. 7 and 9 to offset the adjacent ends of the inner edge of said ring.

55 As best shown in Figs. 7 to 10 the ring 7 is formed in a wave-like manner to provide for

engagement of the inner edge thereof at a plurality of spaced points with opposite sides and opposite walls of the thread of a lamp screw shell 10, which provides for relatively rigid support 5 of a lamp 11 and insures intimate electrical contact between said shell and said ring. The ring 7 is preferably formed of metal which is sufficiently thick and sufficiently resilient to prevent permanent distortion thereof by insertion of a 10 lamp screw shell.

The bottom wall of the circular recess 3 is provided with a shallow rectangular recess 12 which is adapted to receive the inwardly offset portion of a center lamp contact 13. The outwardly 15 offset portion of contact 13 is located substantially centrally of the bottom wall of recess 3.

The inner face of base 2 is provided with a relatively shallow circular recess 14, the bottom wall of which is provided with the recesses 15, 16 and 20 17, the latter being adapted to receive the terminal elements 18, 19 and 20, respectively. The terminal 25 18 is provided with a threaded opening adjacent to each end thereof, one of said openings being arranged to receive a binding screw 21 and the other being arranged to receive the threaded end of a screw 22, the head of which abuts against the outer face of ring 7 and the shank of which penetrates aligned openings in said ring and in the base 2 through the boss 5, 30 said screw serving to hold said base, ring and terminal in assembled relation and also to provide an electrical connection between said ring and said terminal. The ring 7 is further secured to base 2 by a screw 23, the head of which is seated in a circular recess in the bottom wall of recess 14 (Fig. 2) and the threaded shank of which penetrates an opening in the base 2 through the boss 6 and threads into a threaded opening in said ring (Fig. 5).

40 The terminals 19 and 20 are of like form and one end of each comprises a substantially rectangular portion which is adapted to overlie the horizontally bent foot of each of the contacts 24 and 25. The rectangular portions of the terminals 19 and 20 are provided with threaded 45 openings located centrally thereof. The head of a screw 26 abuts the inwardly offset portion of the center lamp contact 13 and the threaded shank thereof penetrates aligned openings in said contact, in the wall separating recesses 12 and 50 16 and in the foot of contact 24, taking into the threaded opening in the rectangular portion of terminal 19, thus holding said center lamp contact, the contact 24, the terminal 19 and base 2 55 in assembled relation and also providing an electrical connection between the lamp contact 13 and the terminal 19.

The terminal 20 and the contact 25 are held in assembled relation with the base 2 by a screw 60 27, the head of which is seated in a recess in the bottom wall of recess 3 and the threaded shank of which penetrates aligned openings in the wall separating recess 3 and terminal recess 17 and in the foot of contact 25, and takes into the threaded opening in the rectangular portion of terminal 20. The contacts 24 and 25 are located diametrically opposite to each other a short 65 distance to either side of the axis of base 2, the vertically projecting portions of said contacts being bowed toward each other intermediate their ends to provide for resilient and intimate engagement with a pair of contact blades.

The opposite ends of terminals 19 and 20 comprise substantially circular portions which are 70 joined to said rectangular portions by narrow 75

necks, said circular portions having threaded openings located centrally thereof and adapted to receive the binding screws 28 and 29. Suitable recesses (not shown) are provided in the bottom walls of the terminal recesses 15, 16 and 17 for the accommodation of the shanks of binding screws 21, 28 and 29.

A molded insulating cover member 30 of circular form is adapted to overlie the terminals 18, 19 and 20, said cover member having a pair 10 of rectangular entrance passages 31 and 32 extending therethrough, the inner portions of said passages being enlarged to provide shoulders beneath which the upper ends of the contacts 24 and 25 are located to prevent fouling of the 15 latter by the plug jacks which are adapted to cooperate therewith. The cover 30 is secured to base 2 by the screws 33 and 34, the threaded shanks of which penetrate openings in said cover and take into the tubular internally threaded 20 elements 35 and 36.

The tubular elements 35 and 36 are located diametrically opposite to each other in line with the contacts 24 and 25, the element 35 being located between the contact 24 and the periphery 25 of base 2 while the element 36 is located between the contact 25 and the periphery of said base. Said elements are of like form, being provided at their outer ends with the shoulders 37 which are adapted to seat within shallow recesses 30 in the bottom wall of recess 3, the tubular portions of said elements penetrating openings extending through the wall between the recess 3 and the recess 14 in base 2, the same being upset at their inner ends over the bottom wall of recess 35 14 to hold said elements in assembled relation with said base.

The outer face of the cover 30 is provided with an annular recess 38 which is adapted to receive an annular projection 39 on the enclosing case 40 40 of a refrigerator motor controller 52. The head of the screw 33 is adapted to seat within a circular recess in the bottom wall of the annular recess 38. The head of the screw 34 abuts against the foot portion of a bracket 41 and the 45 threaded shank thereof penetrates aligned openings in said foot portion and in cover 30 and takes into the tubular element 35 as aforementioned.

A substantially rectangular recess is provided 50 in the upper face of cover 30 adjacent to the periphery thereof to receive the foot portion of bracket 41, the peripheral rim 42 surrounding the recess 38 terminating at the sides of said recess to accommodate said bracket as shown in Figs. 1 and 5. The outwardly projecting portion 43 of bracket 41 is substantially parallel to the axis 55 of the connector 1, said projecting portion being bent at an angle of substantially ninety degrees with respect to the foot of said bracket. The projecting portion 43 of the bracket 41 is provided with a threaded opening 44 for the reception of the threaded shank of a screw 45 (Fig. 6).

As shown in Figs. 2 and 4, the binding screws 21, 28 and 29 are closely grouped adjacent to the periphery of base 2. The cover 30 is provided with a relatively large opening 46 (Fig. 1) which is located substantially in alignment with the binding screw 28, the binding screws 21 and 29 being disposed on opposite sides of said opening. The wires 47, 48 and 49 are shown diagrammatically in Fig. 4, the same being actually brought through the opening 46 and connected to the terminals 20, 19 and 18, respectively, by the binding screws 29, 28 and 21, said wires being 70 75 75

preferably combined in the form of a three-wire conductor cord.

Attachment of the connector 1 to the controller case 40 is effected by registering the passages 31 and 32 with the plug jacks 50 and 51 and pressing the connector into the position indicated by dotted lines in Fig. 6 to effect engagement of said jacks with the contacts 24 and 25 in a well-known manner, as illustrated in Fig. 4. 10 The connector 1 is rigidly secured to the case 40 by tightening of the screw 45 against the segmental ridge or projection 39.

The circuit connections of Fig. 4 are as follows:

15 One side of the compressor motor M is connected to line L¹, the other side being connected to line L² by the conductor 47, to and through terminal 20, the resilient contact 25, contact blade 51, through the automatic temperature responsive control 52, contact blade 50, resilient contact 24, terminal 19, by conductor 48 to line L². A portion of a refrigerator box is shown schematically at 53 and a portion of a refrigerator door at 54. A normally closed switch 55 (shown schematically) is adapted to be held in open position by the door 54 when the latter is closed. Upon opening the door 54 the switch 55 closes, thus completing a circuit for the lamp 11 which circuit may be traced from line L¹ through 30 the switch 55 by conductor 49 to and through terminal 18, the screw 22, the ring contact 7, the lamp screw shell 10 and the filament of the lamp 11, through the center lamp contact 13, the screw 26 and terminal 19 by the conductor 48 35 to line L².

It is apparent from the foregoing that connection of the various electrical devices of a refrigerator to a current supply may be simply and conveniently effected by means of the aforementioned connector and that the appearance of the wiring will be much neater. It is to be understood that the lamp 11 will be located within the refrigerator cabinet to be illuminated upon opening of the refrigerator door in the usual manner.

40 The embodiment of our invention illustrated by the accompanying drawing and described herein fulfills the stated objects in that among other features the construction of the connector is simple, the parts thereof are so formed as to facilitate assembly thereof, and the same are arranged to provide convenient means for effecting the necessary wiring connections.

What we claim as new and desire to secure by Letter Patent is:

55 1. A service connector for electric refrigerators comprising a molded insulating base of cylindrical form, said base having a relatively deep substantially cylindrical recess formed in one end thereof and a relatively shallow substantially cylindrical recess formed in the other end thereof with a disk-like wall formed therebetween, center and screw shell lamp socket contacts located in said relatively deep recess, three wiring terminal members located in spaced relation to each other 60 on the surface of said wall within said relatively shallow recess, a pair of plug jack engaging contacts clampingly engaged by two of said terminal members, said contacts extending outwardly from said relatively shallow recess, screws penetrating said wall and engaging the respective terminal members to secure the latter and all of said contacts in assembled relation to said base, certain of said screws providing mechanical and electrical connections between the contacts on opposite sides of said wall and their associated terminal members, an insulating cover member of circular form adapted to overlie said terminal members and said plug jack engaging contacts, said cover member having recesses formed in the inner face thereof to accommodate said last mentioned contacts, said cover member also having restricted passages opening 45 to the outer face thereof and communicating with said recesses to provide for cooperative engagement of said last mentioned contacts with said pair of plug jacks, said base having internally threaded elements associated therewith and 50 screws penetrating said cover member and engaging said elements to hold said base and said cover member in assembled relation, said cover member having a recess formed in the outer surface thereof to accommodate a projection 55 formed on a suitable support, a metal angle bracket attached to said cover member by one of said last mentioned screws and having a portion thereof adapted to exteriorly overlap said projection, said portion having a screw in 60 threaded engagement therewith, the inner end of said screw being movable into clamping engagement with said projection to rigidly hold said connector against separation from the support.

65 2. A service connector comprising a molded insulating cover member of cylindrical form adapted to overlie said terminal members and said plug jack engaging contacts, means comprising a pair of internally threaded elements carried by said wall and a pair of screws penetrating said cover member and said internally threaded elements to provide for releasable securement of said cover member to said base, said cover member having recesses formed in the inner face thereof to accommodate said plug jack engaging contacts, said cover member having restricted passages opening to the outer face thereof and communicating with said recesses to provide for reception of a pair of plug jacks, and said cover member having an opening forming a passage for three wires to be attached to the respective terminal members.

20 3. A service connector comprising a molded insulating base of cylindrical form, said base having a relatively deep substantially cylindrical recess formed in one end thereof and a relatively shallow substantially cylindrical recess formed in the other end thereof with a disk-like wall formed therebetween, center and screw shell lamp socket contacts located within said relatively deep recess, three wiring terminal members located in spaced relation to each other 25 on the surface of said wall within said relatively shallow recess, a pair of plug jack engaging contacts clampingly engaged by two of said terminal members respectively, said contacts extending outwardly from said relatively shallow recess, screws penetrating said wall and engaging the respective terminal members to secure the latter and all of said contacts in assembled relation to said base, certain of said screws providing mechanical and electrical connections between the contacts on opposite sides of said wall and their associated terminal members, an insulating cover member of circular form adapted to overlie said terminal members and said plug jack engaging contacts, said cover member having recesses formed in the inner face thereof to accommodate said last mentioned contacts, said cover member also having restricted passages opening 40 to the outer face thereof and communicating with said recesses to provide for cooperative engagement of said last mentioned contacts with said pair of plug jacks, said base having internally threaded elements associated therewith and 45 screws penetrating said cover member and engaging said elements to hold said base and said cover member in assembled relation, said cover member having a recess formed in the outer surface thereof to accommodate a projection 50 formed on a suitable support, a metal angle bracket attached to said cover member by one of said last mentioned screws and having a portion thereof adapted to exteriorly overlap said projection, said portion having a screw in 55 threaded engagement therewith, the inner end of said screw being movable into clamping engagement with said projection to rigidly hold said connector against separation from the support.

70 3. A service connector for electric refrigerators comprising a molded insulating base of cylindrical form having a substantially cylindrical recess formed therein and extending inwardly from the outer face thereof, center and screw shell lamp socket contacts located in said recess, said screw shell socket contact comprising a relatively thin punched sheet metal ring-shaped member of circumferentially undulating form whereby a multiplicity of circumferentially spaced portions 75

thereof are adapted for a relatively close fit with the opposed walls respectively of the screw shell thread of an electric lamp, the adjacent walls of which screw shell thread are relatively more 5 widely spaced than the thickness of said sheet metal member, three wiring terminal members located in spaced relation to each other on the inner face of said base, a pair of plug jack engaging contacts having base portions respectively 10 engaged by two of said terminal members, screws penetrating said base, said contacts and said terminal members to secure the same in assembled relation, certain of said screws providing mechanical and electrical connections between 15 said contacts and the terminal members respectively associated therewith, an insulating cover member removably secured to said base and adapted to overlie said terminal members and said plug jack engaging contacts, said cover 20 member having recesses formed therein to accommodate said plug jack engaging contacts, and said cover member also having restricted passages formed therein and communicating with said recesses to guide the movement of said last 25 mentioned contacts into cooperative engagement with a pair of plug jacks.

4. As an article of manufacture, a relatively thin punched sheet metal ring-shaped member having a substantially rectangular notch in the 30 inner edge thereof, the portions of said ring adjacent to said notch being offset relatively to each other to provide for insertion therebetween of the screw shell thread of a lamp, said ring being bent in opposite directions at a number of spaced points 35 between the portions thereof adjacent to said notch to render the same of circumferentially undulating form whereby a multiplicity of circumferentially spaced portions thereof are respectively adapted for frictional engagement with 40 each of the opposite walls of a pair of vertically spaced portions of the lamp screw shell thread, the thickness of said sheet metal member being substantially less than the distance between the opposite walls of the screw shell thread of the 45 lamp to be employed therewith.

5. A service connector attachment for electric refrigerators comprising a molded insulating casing having a wiring cavity formed therein, said casing having a conductor passage communicating with said cavity, at least three wiring terminal members located within said cavity, a pair of plug jack engaging contacts located within said cavity and associated with two of said terminal members respectively, said casing having a substantially cylindrical recess formed in the face 50 thereof opposite to said wiring cavity, center and screw-thread type lamp socket contacts located within said recess, and one of said two terminal members and a third terminal member being 55 adapted to provide for connection of said center and screw-thread type lamp socket contacts to a source of current supply independently of the other of said two terminal members.

6. A service connector attachment for electric refrigerators comprising a molded insulating casing having a wiring cavity formed therein, said casing having a conductor passage communicating with said cavity, three wiring terminal members located within said cavity, a pair of plug jack engaging contacts located within said cavity and respectively associated with two of said terminal members, said casing having a substantially cylindrical cavity formed therein and opening to a 10 face thereof opposite to said first mentioned cavity, center and screw-thread type lamp socket contacts located within said cylindrical cavity, one of said two terminal members being electrically connected with said center lamp socket contact, and the third terminal member being electrically connected with said screw-thread type lamp socket contact. 15

7. A service connector attachment for electric refrigerators comprising a two-part insulating casing having a wiring cavity formed therein, said casing having a conductor passage communicating with said cavity, three wiring terminal members located in spaced relation to each other within said cavity, a pair of plug jack engaging 20 contacts positioned within said cavity and respectively connected with two of said wiring terminal members, said casing having a substantially cylindrical recess formed therein and opening to the face thereof opposite to said wiring cavity, center and screw-thread type lamp socket contacts located within said recess, one of said last mentioned contacts being electrically connected with one of said two wiring terminal members and the other of said last mentioned contacts being electrically connected with the third wiring terminal member, and associated means for removably securing said attachment against accidental displacement when plugged onto a refrigerator part. 25

8. A service connector for electric refrigerators comprising a molded insulating casing having a wiring cavity formed therein, said casing having a conductor passage communicating with said cavity, at least three wiring terminal members located within said cavity, a pair of plug jack 30 engaging contacts located within said cavity and respectively associated with two of said terminal members, said casing being formed to provide guide-ways leading to said contacts to facilitate cooperative engagement of the latter with a pair 35 of plug jacks, said casing having a substantially cylindrical cavity formed therein and opening to a face thereof opposite to said first mentioned cavity, center and screw-thread type lamp socket contacts located within said cylindrical recess, one of said two terminal members being electrically connected with said center lamp socket contact, and the third terminal member being electrically connected with said screw-thread type lamp socket contact and with a suitable source 40 of current supply. 45
